Inventor
Carl Müller

CARL MÜLLER, OF NEW YORK, N. Y., ASSIGNOR TO NICHOLAS MÜLLER, OF THE SAME PLACE.

Design No. 3,296, dated December 15, 1868.

DESIGN FOR A FIGURE.

The Schedule referred to in these Letters Patent and making part of the same.

To all whom it may concern:

Be it known that I, CARL MÜLLER, of the city, county, and State of New York, have invented a new and useful Design for a Figure; and I do hereby declare that the following is a full, clear, and exact description thereof, which will enable those skilled in the art to make and use the same, reference being had to the accompanying drawing, forming a part of this specification.

This invention relates to a design for a figure, representing a New York boot-blacker running along in the streets. Under his left arm he carries his box of "tools," while, with his right, he holds up a brush, asking some one for a job. His hair hangs on his forehead, from

under his cap, his long coat hangs loosely on his shoulders, and his shirt-bosom is thrown open, as seen in the photograph. Behind the figure, and to its right, a common street-hydrant may be seen.

What I claim as my invention, and desire to secure by Letters Patent, is—

The design for a figure, as herein shown and described.

The above specification signed by me, this 11th day of November, 1868.

CARL MÜLLER.

Witnesses:

JOHN W. WILLIAMS,
HENRY RASSIGA.
